UNITED STATES PATENT OFFICE.

PAUL FLEMMING COX, OF BATTLECREEK, MICHIGAN.

GAME APPARATUS.

SPECIFICATION forming part of Letters Patent No. 789,006, dated May 2, 1905.

Application filed June 22, 1904. Serial No. 213,658.

To all whom it may concern:

Be it known that I, PAUL FLEMMING Cox, of Battlecreek, in the county of Calhoun and State of Michigan, have invented certain new and useful Improvements in Game Apparatus; and I hereby declare that the following is a full, clear, and exact description thereof, reference being had to the accompanying drawings, which form part of this specification.

This invention is a novel game apparatus, toy, or puzzle; and it consists in a holder or box having a plurality of suspending devices, such as hooks or eyes, attached to its side wall above its bottom and below its top and a plurality of loose objects in the box adapted to be suspended from said devices, said objects preferably containing eyes or hooks adapted to engage the hooks or eyes on the box. Only one object can be suspended from one device, and considerable patience or skill is required to suspend the plurality of objects on the hooks, as the objects cannot be handled directly and must be positioned by manipulating the box in which they are contained.

The invention is concisely stated in the claims, and will be clearly understood from the following description, in connection with the drawings, in which—

Figure 1 is a front view of the preferred form of game apparatus embodying my invention with the objects detached from the hooks. Fig. 2 is a perspective view thereof, showing the objects suspended. Fig. 3 is a section on line 3-3, Fig. 1. Figs. 4, 5, and 6 are details showing the hooks.

The box A is adapted to be held in the hand and is preferably provided with a glass or mica front B. It may be of any desired form. Attached to and projecting inwardly from the side walls of the box are a series of suspending devices C, preferably hooks or eyes, set at different angles, which are arranged intermediate the glass B and bottom a of the box, so that objects cannot be directly engaged therewith while lying flat on the bottom or top of box. Within the box are a number of separate movable objects D, (two being shown,) corresponding in number to the devices C. As shown in Fig. 1, these objects are dummy figures of men, and said figures

have eyes or hooks d on their heads bent or projecting at different angles thereto by which they can be suspended from the hooks or eyes in the box when properly engaged therewith.

The game may be called "Hang the Bandits," and the player must so manipulate the box in the hand as to engage the dummy figures with the suspending devices, the object being to hang the bandits all together, which, owing to the location of the suspending devices on the sides of the box and the gravity of the objects, is difficult, and this difficulty is enhanced by the number of the objects in the box.

Preferably the hooks C are stamped out of sheet metal with head portions c, which are bent over at right angles to the shanks. Then the ends c' of this part c are bent upward, forming staples, which may be forced through the wall of the box A and clenched, as indicated in Figs. 4 and 5, thus securing the hooks in place.

The whole box may be covered with a finishing-paper E, as indicated in the drawings. Preferably the hooks are set at different angles, and the eyes d of the dummies are bent at different angles, so as to increase the difficulty of playing the game. In practice the dummy with straight eye should be engaged with the straight right-handed hook. Then the other dummy can be caught on the other hook by properly manipulating the box.

I prefer to use a plurality of the suspending devices and plurality of loose disconnected objects, as it increases the difficulty of executing the trick. Further, it will be noted the suspending devices are attached to the sides of the box, so that practically the objects can pass all around the suspending devices without at any time, when in any normal position of rest, being in position to engage therewith.

Having thus described my invention, what I claim as new, and desire to secure by Letters Patent, is—

1. The herein-described toy, comprising a box or casing, a plurality of suspending-hooks attached to one side thereof and projecting inwardly therefrom between the top and bottom of the box and set at different angles; 100

with a plurality of loose objects loosely confined in the box and provided with eyes by which they can be respectively suspended on the respective hooks by skilful manipulation 5 of the box, substantially as described.

2. The herein-described game apparatus, comprising a box with a transparent top, a plurality of hooks attached to one side of the box and projecting inwardly therefrom inter-
10 mediate the top and bottom of the box, said hooks being turned to face at different angles, and a like number of movable objects loosely confined in the box each provided with an eye

on one end and adapted to be thereby hung upon the respective hooks by manipulation 15 of the box in the hand, the eyes being also arranged at different angles relative to their connected objects, substantially as described.

In testimony that I claim the foregoing as my own I affix my signature in presence of two 20 witnesses.

PAUL FLEMMING COX.

In presence of—

FRANCIS A. KULP,
FRANK H. MOTT.
